A loading device for placing a substance in a pre-rolled cone, as shown and described.

DESCRIPTION

FIG. 1 is a perspective view of the loading device for placing a substance in a pre-rolled cone;

FIG. 2 is a front view of the loading device for placing a substance in a pre-rolled cone;

FIG. 3 is a rear view of the loading device for placing a substance in a pre-rolled cone;

FIG. 4 is a first side view of the loading device for placing a substance in a pre-rolled cone;

FIG. 5 is a second side view of the loading device for placing a substance in a pre-rolled cone;

FIG. 6 is a top view of the loading device for placing a substance in a pre-rolled cone; and,

FIG. 7 is a bottom view of the loading device for placing a substance in a pre-rolled cone.
